Application June 28, 1950, Serial No. 10,806

Term of patent 14 years

(CL. D7—5)

To all whom it may concern:

Be it known, that I, Edward A. Sprigg, a citizen of the United States, residing at East Orange, in the county of Essex and State of New Jersey, have invented a new, original, and ornamental Design for a Shoe Sole, of which the following is a specification, reference being had to the accompanying drawing, forming part thereof.

In the drawing:

Fig. I is a plan view of a shoe sole showing my new design.

Fig. II is a side elevation of the shoe sole shown in Fig. I.

Fig. III is a cross sectional view taken substantially on the line III—III of Fig. I.

I claim:

The ornamental design for a shoe sole, as shown.

EDWARD A. SPRIGG.
